Assistant Examiner — Yelizaveta Y Masalimova

(74) Attorney, Agent, or Firm — McAndrews Held & Malloy, Ltd.

(57) CLAIM

The ornamental design for an article of footwear, as shown and described.

DESCRIPTION

FIG. 1 is a rear photographic view of an article of footwear showing our new design;

FIG. 2 is a front perspective photographic view thereof;

FIG. 3 is a front photographic view thereof;

FIG. 4 is a medial side photographic view thereof;

FIG. 5 is a bottom photographic view thereof; and,

FIG. 6 is a top photographic view thereof.

The dashed broken lines and the halftone areas bounded by the dashed broken lines illustrate portions of the article of footwear that form no part of the claimed design.

1 Claim, 6 Drawing Sheets
